UNITED STATES PATENT OFFICE.

WILLIAM H. EGGBRECHT, OF GRAND RAPIDS, MICHIGAN, ASSIGNOR TO CHENEEY
TALKING MACHINE COMPANY, OF CHICAGO, ILLINOIS, A CORPORATION OF
ILLINOIS.

DESIGN FOR A CASING FOR AUTOMATIC SOUND-PRODUCING INSTRUMENTS.

53,067.

Specification for Design.

Patented Mar. 11, 1919.

Application filed October 31, 1918. Serial No. 260,616. Term of patent 7 years.

To all whom it may concern:

Be it known that I, WILLIAM H. EGGBRECHT, a citizen of the United States, residing at Grand Rapids, in the county of Kent and State of Michigan, have invented a new, original, and ornamental Design for Casings for Automatic Sound-Producing Instruments, of which the following is a specification, reference being had to the accompanying drawing, forming part thereof.

The figure is a perspective view of a casing for automatic sound producing instruments, showing my new design.

I claim:

The ornamental design for a casing for automatic sound producing instruments, substantially as shown.

WILLIAM H. EGGBRECHT.
